UNITED STATES PATENT OFFICE

WALTER L. DOWNEY, OF RICHMOND, VIRGINIA

CUSHION SIDE BEARING

Application filed February 23, 1926. Serial No. 90,193.

The object of this invention is to provide body and truck bolsters, or either of them, with cushion side bearings, which not only perform the usual functions of side bearings, but in addition take up the strains of oscillation of the car in use and prevent the sharp blow on the truck bolsters which is transmitted to the bolster springs, and thereby saves much expense in repair work and adds to the security as well as safety of the cars equipped with such cushion side bearings.

The invention consists in interposing between the body and truck bolsters boxes containing springs which are yieldingly held therein by a movable cover plate, the springs being secured within the box under compression and the parts being readily accessible for assembly and repair purposes, as I will proceed now to explain and finally claim.

In the accompanying drawings illustrating the invention, in the several figures of which like parts are similarly designated, Fig. 1 is a top plan view; Fig. 2 a lengthwise elevation, and Fig. 3 and end elevation of the assembled parts ready for application to a bolster. Fig. 4 is a longitudinal section taken in the plane of line 4—4, Fig. 1, and Fig. 5 is a transverse section taken in the plane of line 5—5, Fig. 1. Fig. 6 is a view similar to Fig. 4 showing the parts in process of assembly.

Without thereby limiting the invention to the after-mentioned details, excepting as these details are hereinafter claimed, I will proceed to explain one embodiment of my invention that may be used on freight and other cars.

1 is a box, which may be a casting or a forging, having the bottom 2, circumscribing wall 3, a partition 4 or any number of such partitions, where more than one spring is used, and an open top surrounded on three sides by an outwardly extending flange 5. In the instance shown, two coiled springs 6 are used and each occupies a separate chamber within the box, the partition 4 serving to divide the box, as already indicated, into as many spring pockets as there are springs. The bottom is provided with as many open-

ings 7 as there are springs, and these openings are encircled by the bosses 8 which serve as centering devices for the springs 6.

The openings 9 are drain holes for the pockets.

A cover plate 10, is provided for the box, and it has a downwardly extending and re-entrant flange 11 on three sides which engages the flange 5 of the box when said cover plate is applied thereto by a sliding movement. The other end 12 of the cover plate is left open and extends sufficiently far beyond the adjacent end of the box to receive a transversely arranged bolt 13, or other connecting medium by which the cover plate is held in place on the box.

The flange 11 is spaced apart a distance greater than the thickness of the flange 5 so as to allow the necessary rising and falling of the cover plate to get the cushioning effect of the springs 6.

As will be seen especially upon reference to Fig. 1, the box and its cover plate are described on an arc of a circle to provide for the swinging movement of the car truck.

The box has at its bottom the laterally extended lugs 14, which may be buttressed against the circumferential wall of the box by the webs 15, and these lugs are adapted to receive bolts or other means by which the box is fastened to the bolster.

The springs 6 are arranged in the box under compression, and this is effected by the use of spring caps 16 having internally threaded portions fitted within the springs, 85 with their threaded openings in line with the unthreaded openings 7 in the bottom of the box, and these internally threaded caps are adapted to receive bolts 17 passed up from below through the openings 7 and engaged with the caps. When the parts are thus arranged, the cover plate is put in place and fastened therein by the bolt 13, and then the bolts 17 are removed. One way of assembling the parts is to put the spring box 95 on the platen of a press; then put the spring or springs in the spring box; then put a spring cap on each spring, and then cause the press to compress the spring or springs, and while so compressed the holding bolts 100

17 are screwed into the spring caps, and this may be done by hand and without using a tool, and then the press is released and while the spring or springs is or are held under 5 compression the cover plate is put in place and secured by the key bolt or other fastening 13, and then the holding bolt or bolts is or are removed, but inasmuch as they are under the tension of the spring or springs, it 10 will be necessary to use a tool, such as a wrench.

Not only do the caps 16 function as just 15 previously described, but having their threaded portions entering the springs they 15 tend to keep the springs upright, that is to say, prevent them from cocking.

Some of the advantages incident to my invention are as follows:—In use the cushion side bearing starts at zero and sets up retardation and cushions the oscillations, and 20 does not allow the sharp blow on the truck bolster to be transmitted to the bolster springs, and, therefore, the present invention overcomes the tendency of the bolster 25 springs to go solid and break. It is designed to permit only about a quarter of an inch side bearing clearance as the maximum, and it can be adjusted if necessary. The springs are protected by the spring box and cannot 30 go solid. These springs are under sufficient compression to eliminate any undesired kick-back, and this compression is sufficient for the afore-mentioned retardation at the 35 start of oscillation. It is well known that 35 failures in bolster springs are the result of sharp blows transmitted by the weight of the rocking car through the side bearings and bolsters, and the cushion side bearing of this invention will absorb these blows at the 40 instant they are started. This action results approximately in twenty per cent of the load 45 limit of the bolster springs being absorbed, and, indeed, a very considerable retardation of the oscillations is accomplished before the 50 bolster springs are called upon to perform the additional work necessitated by the rolling of the car. This retardation in its 55 fancy will set up a time element in the oscillations that will approximately decrease 55 the critical speed three times what it is with the old constructions, and consequently 60 puts the critical speed of heavily loaded cars a safe distance below normal operating speeds on railroads. Further, this cushion 65 side bearing will also absorb the sharp blows incident to former constructions, and thus prevent the breaking of the side bearings, and will constantly reduce the blows which cause bent and broken bolsters. It also 65 absorbs the sharp blows that otherwise would be imposed on the road bed, and consequently reduces maintenance costs. Furthermore, the cushion side bearing is so designed as not to cause undue friction on track curves. 65 The maintenance cost of the cushion side

bearing would be practically zero, inasmuch as the springs and castings should last the life of the ordinary car unless damaged or broken in accident.

The parts constituting the box and its 70 cover plate and the spring caps may be cast or forged.

The spring boxes of the cushion side bearings may be bolted, riveted, welded or cast 75 integral with the truck bolster or the body bolster or their equivalents or substitutes.

When the car is in vertical position, the top and bottom side bearings on the body and truck bolsters are just in contact, and without friction. When one side of the 80 truck falls into a low joint in the track, thereby causing the opposite side of the truck to start oscillation of the body with a sharp blow, the cushioning will maintain the heavy blow to the truck, and instead of 85 the side of the truck striking the low joint coming up and striking the body another heavy blow to start excessive rolling of the car body, the springs on that side will assist in putting the car body in proper position; but the springs in the cushion side bearing will immediately cease functioning when the 90 opposite bearing comes into contact. In other words, the springs will stop functioning when the car is in upright position, thereby preventing any kick-back of one 95 spring against the other.

What I claim is:—

1. A cushion side bearing, comprising a 100 spring box, a spring therein, a cover plate, means for effecting the connection of the box and cover plate by a lengthwise sliding movement, and means to fasten the cover plate upon the box to permit its up and down movement relative to the box as the 105 spring expands and contracts.

2. A cushion side bearing, comprising a 110 spring box having a bottom and an open top, said top having an outwardly extending flange extending around three sides, a spring in said box, a cover plate having a downwardly extending flange on three sides adapted to engage the flange on the box, and a transverse bolt engaging the box and the flange on the cover plate.

3. A cushion side bearing, comprising a 115 spring box having a bottom and an open top, said top having an outwardly extending flange extending around three sides, a spring in said box, and a cover plate having a downwardly extending flange on three sides adapted to engage the flange on the box by a lengthwise sliding movement.

4. A cushion side bearing, comprising a 120 spring box having a bottom and an open top, said top having an outwardly extending flange extending around three sides, a spring in said box, and a cover plate having a downwardly extending reentrant flange on three sides adapted to engage the 130

flange on the box by a lengthwise sliding movement and the flange on the cover plate having sufficient depth to permit a yielding movement in service.

5 In testimony whereof I have hereunto set my hand this 20th day of February A. D. 1926.

WALTER L. DOWNEY.
